GAS GUN

Charles J. Manville, Pontiac, Mich.

Application October 5, 1935, Serial No. 43,685

5 Claims. (Cl. 42—1)

This invention relates to guns and more particularly to a gun of the multiple cartridge magazine form designed to discharge gas or fluid projectile by the firing or explosion of cartridges or shells containing fluid producing substances.

5 The invention embraces the provision of a relatively small compact gun of the double action revolver type for discharging tear gas or other fluids wherein is embodied a movable cartridge magazine capable of carrying a plurality of cartridges loaded with fluid producing substance, which cartridges may be successively fired or discharged.

10 The invention contemplates the provision of an arrangement of this character wherein the cartridge magazine is made revolvable and wherein the magazine is positively indexed in each successive position to fire a cartridge.

15 The invention contemplates the provision of a fire arm of this character which will accommodate a plurality of cartridges and which will fire the cartridges successively by the manipulation of a single trigger mechanism which may be actuated repeatedly until all of the cartridges have been discharged.

20 A further object of the invention is the provision of a cartridge carrier or magazine formed of comparatively light material whereby the weight of the gun is reduced to a minimum.

25 Another object of the invention is the provision of an improved trigger control mechanism wherein the relative position of the trigger and hammer release may be accurately adjusted.

30 Another object of the invention is the provision of means for rotating the revolvable cartridge magazine and positively indexing the magazine to fire each cartridge.

35 A further object of the invention is the provision of safety means for preventing the firing of the pistol.

40 Further objects and advantages are within the scope of this invention such as relate to the arrangement, operation and function of the related elements of the structure, to various details 45 of construction and to combinations of parts, elements per se, and to economies of manufacture and numerous other features as will be apparent from a consideration of the specification and drawings of a form of the invention which may 50 be preferred, in which:

Figure 1 is a side elevational view illustrating a form of gas gun of my invention;

55 Figure 2 is an end elevational view of a gun illustrated in Figure 1, a portion of the hand grip being broken away;

Figure 3 is a top plan view of the gun illustrated in Figure 1;

Figure 4 is a longitudinal sectional view through the gun of my invention particularly illustrating the cartridge magazine and the trigger and hammer mechanism in normal position;

Figure 5 is a view of the breech and grip portion of the gun showing the trigger mechanism and hammer position just prior to release of the hammer;

Figure 6 is a vertical sectional view taken substantially on the line 6—6 of Figure 1;

Figure 7 is an isometric view of the trigger and hammer arrangement and cartridge magazine actuating means per se of my invention;

Figure 8 is a vertical sectional view taken substantially on the line 8—8 of Figure 5, particularly illustrating the cartridge magazine and indexing means therefor;

Figure 9 is an isometric view illustrating the safety means to prevent firing of the gun;

Figure 10 is a fragmentary sectional view through the safety means forming a part of the invention, the view being taken on line 10—10 of Figure 6;

Figure 11 is a fragmentary sectional view showing the firing pin arrangement, the section being taken substantially on the line 11—11 of Figure 5;

Figure 12 is an isometric view showing the configuration of a shell or cartridge of the character utilized in the gun of my invention.

30 While I have shown the arrangement of my invention as designed to carry a predetermined number of cartridges, it is to be understood that I contemplate the utilization of the arrangement of my invention in any construction wherein the same may be found to be applicable.

35 Referring to the drawings in detail, the gun as illustrated is inclusive of a stock or handle portion 10 which is preferably made in two half sections 11 and 12 and a barrel 13, the latter having an integrally formed rearwardly extending portion 14 which is secured to the two sections 11 and 12 also being held together through the handle portion by means of a screw 17.

40 Positioned between the barrel 13 and the breech portion 20 is a cartridge carrier or magazine 21 which is preferably fabricated of phenol condensation product or other comparatively light material, which contains a plurality of spaced cylindrical bores or chambers 22 which are adapted to contain cartridges of the character illustrated at 105 in Figure 12. The gun of my invention is 45 illustrated as accommodating cartridges or shells 50 55

substantially the size of an ordinary twelve-gauge shell of a dimension substantially $\frac{1}{8}$ of an inch in diameter, although the gun may be made of a size to take shells of different size, but I have found that the size of shell illustrated accommodates a suitable charge of tear gas which has been found to be satisfactory and effective. The magazine or cartridge carrier 21 when fabricated of Bakelite or phenol condensation product may be moulded to the desired configuration, thus eliminating machining operation upon this element of the construction. The magazine is preferably moulded with exterior flutes 23 so as to reduce the weight of the carrier element to a minimum. The magazine 21 is provided with a central longitudinally extending bore 24 which is provided at one end with an enlarged bore adapted to receive a bushing 25 of hardened steel or other suitable material which preferably has a knurled exterior surface, the bushing being preferably pressed into or moulded integrally with the magazine or cartridge carrier 21. The bushing 25 is provided with rearwardly extending spaced projections 26 in number equal to the number of cartridge chambers or openings in the carrier, which projections are successively engaged in a manner hereinafter described for the purpose of rotating the magazine.

Extending between the breech 20 and a depending projection 28 formed integrally with the barrel portion 13 is a shaft 29 having its rear portion threaded into the breech as at 30 so as to be fixedly secured thereto and its forward portion extending into a bore in the projection 28 and secured thereto by means of a screw 31 or other suitable means. The shaft 29 provides additional reinforcing connecting means between the barrel 13 of the gun and the breech 20 as well as to provide the means for revolably supporting the magazine 21. The bushing 32 is loosely journaled upon the shaft 29 adjacent the forward extremity thereof and is also loosely journaled in the bore 24 of the magazine carrier 21. Interposed between bushing 32 and bushing 25 is an expansive spring 33 which exerts a pressure upon bushing 25 so as to yieldingly urge the magazine toward the breech of the gun so as to retain the projections 26 at all times in the path of the magazine actuating means.

The trigger and hammer mechanism carried by the stock 11 comprises a trigger 35 which is partially slotted as at 36 to accommodate a latch element 38. The trigger 35 is pivoted upon a pin 39 in the breech portion, the pin passing through an opening 40 in the trigger. The walls of the trigger formed by the slot 36 are provided with openings which are in registration with an opening in the latch member 38 and which receive a member 42. The member 42 is formed with an upwardly extending portion 43 having a tapered upper extremity which forms the actuating means engageable with the projections 26 on the bushing 25 to actuate or rotate the cartridge magazine 21 during a portion of movement of the trigger 35, the projecting portion 43 extending loosely through a vertical slot 44 formed in the breech portion of member 11 as particularly illustrated in Figure 6. Thus, the latch member 38 is connected to the trigger member by means also forming the actuating means for the cartridge magazine.

The upper extremity of the latch member 38 is provided with a projection 45 which engages a downwardly extending projection 46 forming a part of the hammer 47, the latter being pivoted

upon a pin 48 passing through an opening 49 in the hammer, the extremities of the pin projecting into interior openings in the portions 11 and 12 of the stock of the gun. The latch member 38 is provided with an opening 50 which receives one end of a contractile spring 51, the other end of which is connected to a pin 52 carried by the stock portion 11 of the gun, the function of the spring 51 being to return the latch 38 to its normal position upon return of the trigger to normal position after the firing of a cartridge.

As illustrated in Figures 4, 5 and 6, the portion 11 is provided with a laterally extending boss 55 which is provided with aligned bores 56, 57 and 58 as particularly shown in an enlarged view in Figure 11, the bore 56 receiving the firing pin 60 which has an enlarged portion 61 and a still further enlarged rear flange 62. A coil spring 63 is positioned in the bore 57 between flange 62 and the end wall of the bore and serves to normally urge the firing pin 60 away from the cartridges in the magazine 21. A laterally positioned screw 65 is carried by the stock portion 11, the head of the screw 65 serving to hold the firing pin within the bore 56 in the breech portion of the gun and thus serves to limit the rearward movement of the firing pin.

In order to retain the magazine actuating member 43 in engagement with the bushing 25, there is provided a U-shaped or "hair pin" spring 69, one end of which projects into an opening 70 in the interior side wall of the stock portion 11, the free extremity having a projecting portion 71 which engages the member 43. With the trigger and hammer mechanism in normal position as illustrated in Figure 4, the magazine actuating member 43 does not contact with bushing 25, its movement being limited by means of a pin 72 so that upon movement of the trigger 35 and upward movement of the magazine actuating member 43, the pin will direct the latter into engagement with one of the projections 26 to partially rotate the cartridge magazine. The hammer 47 is urged into engagement with the firing pin at all times by means of a comparatively stiff plate spring 74, one end of which engages the hammer, the other end being positioned between two projecting lugs 75 formed on the lower portion of the stock portion 11.

The latch member 38 is provided with a forwardly extending finger 77 which cooperates in a manner to be hereinafter explained with a series of steps 78 formed on the rear portion of the cartridge magazine as particularly shown in Figures 5 and 8, there being a number of indentations or steps corresponding to the number of cartridge chambers. The purpose of finger portion 77 is to positively index or position the cartridge magazine so that each individual shell in firing position will be in an accurate location in registry with the barrel 13.

The latch member 38 is provided with a depending portion 80 which when the trigger has been moved a predetermined amount is engaged by a member 81 threaded into a bore 82 in the trigger, the threaded member 81 having a kerf 83 adapted to receive a suitable tool for adjusting the position of the threaded member 81. The function of screw 81 is to determine the position of release of the firing hammer when the trigger 35 is moved slightly beyond the position of the mechanism as illustrated in Figure 5. The trigger 35 is also provided with a threaded opening to receive a screw 85 which serves to lock the adjusting screw 81 in proper position.

The gun of my invention embodies a safety means for preventing firing of the gun which consists in a stud shaft 87 journalled in a transversely extending bore in the breech portion of 5 the stock 11, the shaft having an enlarged head portion 88. The extremity of the stud 87 is cut away to form a flat surface 89 as particularly illustrated in Figures 5 and 9. The stock portion 11 is provided with a recess 90 (see Figure 3) 10 which accommodates the head portion 88 of the safety device, the stock portion also being provided with an arcuate depression 92 as illustrated in Figure 10. Extending transversely of the head portion 88 is a bore 93 within which is ar- 15 ranged a plunger 94 having a reduced portion 95 and a knurled finger piece 96. Surrounding the portion 95 and positioned in the bore 93 is an expansive spring 97 which serves to urge the plunger 94 in the direction of the arcuate groove 20 92, the plunger 94 being formed with a ball like extremity 98 which projects into the groove 92. The arcuate groove 92 is of a length to permit about ninety degrees of rotative movement of the stud 87 so as to bring the safety means into position to prevent firing of the pistol. For example, referring to Figure 5, if the stud 87 is moved through ninety degrees by means of manipulation 25 of a finger piece 96 (see Figure 10), the stud will be rotated bringing the flat surface 89 to the position shown in dotted lines in Figure 5, thus bringing the cylindrical part of the stud 87 into position to engage the hammer 47 should the trigger of the gun be retracted and thus prevent the hammer from striking the flange 62 upon the 30 35 end of the firing pin.

The assembly of the safety means is accomplished in a simple manner as it is only necessary to retract the plunger 94 by grasping the finger piece 96 until the rounded end 98 is withdrawn 40 from the groove 92 after which the stud 87 and head 88 may be withdrawn laterally from the transverse bore in the breech of the gun.

I have found it desirable to form each bore or chamber in the cartridge magazine with a projection 53 as illustrated in Figures 2 and 4, the 45 purpose of the projection 53 being to prevent the injection of lethal shells of the same caliber into the gun. It is to be understood that the inclusion of projections of this nature in the cartridge 50 chambers are not absolutely necessary except as a safety factor in the use of the gun.

In order to facilitate loading the magazine with cartridges or shells, one of which is illustrated in Figure 12, I have provided the breech portion 55 with a depression or recess 100 which is of a dimension suitable to permit the passage of cartridges into the magazine. In order to retain the cartridges in the magazine, I have provided a movable finger piece 101 pivoted upon a screw 60 102 carried by the breech of the gun, as illustrated in Figures 3 and 6. When it is desired to extrude empty cartridge shells or reload the gun, the finger piece 101 is moved to the position illustrated in dotted lines in Figure 6 so as to leave the depression 100 unobstructed.

Figure 12 illustrates a form of cartridge suitable for use in the gun of my invention comprising a cylindrical portion 105 and a flange portion 106 similar in size to the ordinary type of shell of 70 Number 12 gauge for shot gun purposes. As illustrated, the shell is provided with a longitudinally extending depression or indentation 107 which will permit the projection of the shell into a bore of the magazine as the depression 107 will 75 receive the projection 53, thus preventing the sur-

repetitious use of shells not intended to be used therein. I have found that shells of this size containing tear gas of the character known as chloracetophenone in which the chemical in crystalline form is placed in the shell of this size has been found effective and satisfactory as when the shell is discharged substantially all of the crystalline chemical becomes volatile under the heat of gun powder or other explosive which is placed adjacent the percussion cap on the base 5 of the shell and serves to extrude the crystalline chemical substantially all in volatile or gas form.

The rear portion of the cartridge magazine 21 is sufficiently spaced from the breech to snugly accommodate the flanges 106 of the shells, thus 10 virtually making the rear portion of the magazine substantially gas tight so that little or no 15 gas is extruded at this point during the explosion of the cartridge.

It is to be noted that the bore in the barrel 13 20 in the embodiment of the invention illustrated is slightly larger in diameter than the bores of the cartridge chambers, thus permitting for expansion of the heated gas during the explosion of the cartridge, although it is to be understood that the 25 bore of the barrel 13 may be made the same size as the bore of the cartridge chamber without departing from the spirit of the invention.

The operation of the gun of my invention is as 30 follows: Assuming that it is first desired to load the gun with cartridges of the character shown in Figure 12, the finger piece 101 is swung manually to the position shown in dotted lines in Figure 6, after which the cartridges may be inserted through the depression or recess 100 into the several bores 22 of the cartridge magazine 21, the cartridge magazine being rotated manually to bring the several bores successively into registration with depression 100 to receive the cartridges, after which the finger piece 101 is returned to 40 its normal or closed position as illustrated in full lines in Figure 6 which prevents the removal of the cartridges from the magazine. In order to fire the gun, it is necessary that the safety means be moved to ineffective position, that is, with the 45 shaft of the safety means moved to the position shown in Figures 4 and 6 with the finger piece 96 in a vertical position as illustrated in Figure 10 so that the plane of the flattened portion 89 is parallel with the face of the firing hammer 47. 50

In such position, the firing hammer is permitted to impinge upon the firing pin 63 so that a cartridge may be fired. When it is desired to fire a cartridge, the trigger 35 is moved rearwardly by the forefinger of the operator, the rearward movement of the trigger causing the member 43 to first engage with a projection 26 formed on bushing 25, which rotates with the cartridge magazine 21, this movement of the trigger moving the cartridge magazine one-fifth of its rotation to bring the next succeeding cartridge into firing position. As the trigger is moved rearwardly, the finger 77 forming a part of the latch 38 is moved into the path of the indentations 79 formed exteriorly of the cartridge magazine, the 60 finger piece 77 acting as an indexing means which engages a wall 78 on the cartridge magazine to properly index the latter in cartridge firing position, the position of the respective parts being shewn in Figure 5 with the trigger moved to a 65 rearward or firing position. As the trigger is moved rearwardly, the upper portion of latch member 38 engages the depending portion 46 of the firing hammer causing the firing hammer to rotate about its pivot 48 against the tension of 70 75

the plate spring 74. When the trigger has been moved to its rearmost position in which the finger 77 has properly indexed the cartridge magazine, the end of the screw 81 carried by the trigger engages the depending portion 80 of the latch member so that further slight rearward movement of the trigger causes a release or disengagement of the latch member 38 with the depending portion of the firing hammer 46, at which time 10 the firing hammer 47 under the influence of the force of the plate spring 74 is caused to rapidly impinge upon the flange 62 of the firing pin 60 driving the latter forward to impinge upon the percussion cap which causes the discharge or 15 firing of the tear gas cartridge. After the firing of a cartridge, the finger pressure upon trigger 35 is released and the trigger is returned to its normal position as shown in Figure 4 under the influence of the contractile spring 51 engaging 20 the latch member 38. It is to be noted that the hairpin spring 69 at all times engages the member 43 so that upon successive actuation of the trigger, the member 43 will cause a partial rotation of the cartridge magazine to successive cartridge firing position. The operation above described is repeated until all the cartridges have been fired, after which the finger piece 101 may be moved to the dotted position again as shown 25 in Figure 6 to permit the removal of the empty 30 shells or cartridges.

It is to be noted that the release of the hammer may be accurately coordinated with the indexing of the magazine chamber by means of the adjusting screw 81 which is properly adjusted to 35 engage the latch 38 immediately after the indexing of the cartridge magazine, the screw 81 being locked in position by means of the screw 35.

When it is desired to move the safety means to safety position, as indicated in dotted lines in 40 Figure 5 wherein the plane of the flattened surface 89 is moved to a position parallel with the axis of the cartridge magazine, the cylindrical portion of the shaft 87 is thereby moved in the path of the firing hammer 47 so that the latter 45 is prevented from engaging the flange 62 of the firing pin 60. This rotation of the safety means is accomplished by moving the finger piece 96 through an arc of 90 degrees as particularly shown in Figure 10. One of the features of the 50 invention resides in the assembly of the safety means. For example, when it is desired to remove the safety means for any reason, it is only necessary to exert a longitudinal movement in a direction of the axis of the finger piece 96 against 55 the force of spring 98 so as to withdraw the ball-like portion 98 from engagement with the arcuate recess 92, after which a longitudinal force in the direction of the axis of shaft 87 causes the safety means to be withdrawn from the bore in the stock 60 portion of the gun. To reassemble the safety means, it is only necessary to exert a lateral pressure against the heat 88 in the direction of the axis of shaft 87 and the ball portion 98 will 65 slip into the arcuate recess 92 to the position 5 shown in Figure 10.

It is apparent that within the scope of the invention, modifications and different arrangements may be made other than is herein disclosed, and the present disclosure is illustrative merely, the 70 invention comprehending all variations thereof.

What I claim is:

1. In a gas gun, the combination of a stock; a barrel spaced from the stock and having an extension fixedly connected thereto; a revoluble cartridge carrier positioned between the barrel

and the stock; a shaft connecting said stock and barrel members; said cartridge carrier being journaled upon said shaft; a trigger pivoted to said stock; a firing hammer pivoted to said stock; a latch member pivotally carried by said trigger and arranged to engage and actuate said firing hammer toward cocked position; adjustable means carried by said trigger and located between said trigger and said latch member for releasing said hammer upon a predetermined movement of said trigger; means for rotating said cartridge carrier by movement of said trigger; and means forming an integral part of said latch member for indexing said cartridge carrier upon each successive movement of said trigger. 15

2. In a gas gun, the combination of a stock; a barrel connected to but spaced from said stock and having a cylindrical bore; a magazine having a plurality of cartridge chambers therein rotatably supported between said barrel and stock; trigger mechanism; means associated with said trigger mechanism for successively causing rotative movement of said magazine; resilient means urging said cartridge magazine toward said stock; the bore in the barrel being of a diameter larger than that of a cartridge chamber in said magazine. 20

3. In a gas gun, the combination of a stock having a breech portion; a barrel spaced from said breech portion and having an extension secured to said breech portion; a shaft connecting said barrel and said stock; a revoluble cartridge magazine supported upon said shaft between said barrel and said breech portion; said cartridge magazine having peripherally arranged index indentations; a finger trigger; a hammer; a firing pin; resilient means for normally urging said hammer in contact with said firing pin; a member pivotally connected to said trigger and having a portion engageable with said hammer for retracting and releasing the latter to engage the firing pin upon movement of the trigger and another portion movable into the path of the indentations on said cartridge magazine for indexing the latter; and adjustable means carried by said trigger and engageable with said member for determining the coordination of the magazine indexing portion and the release of the hammer. 45

4. In a gas gun, the combination of a stock having a breech portion; a barrel spaced from said breech portion and having an extension secured to said breech portion; a shaft connecting said barrel and said stock; a revoluble cartridge magazine supported upon said shaft between said barrel and said breech portion; said cartridge magazine having peripherally arranged indentations; a finger trigger; a hammer having a ledge; a firing pin; resilient means for normally urging said hammer in contact with said firing pin; a member connected to said finger trigger for revolving said cartridge magazine; a second member pivotally supported by said finger trigger and having a portion engageable with said ledge on the hammer for retracting the hammer and having a second portion movable into the path of the indentations on said cartridge magazine for retaining the latter in position with respect to the firing pin; and adjustable means carried by said finger trigger and engageable with said second member for determining the coordination of disengagement of said second mentioned member with the hammer ledge and the engagement of the second portion thereof with 75

the indexing indentations of the cartridge magazine.

5. In a gas gun, the combination of a stock having a breech portion; a barrel spaced from said breech portion and having an extension secured to said breech portion; a shaft connecting said barrel and said stock; a revolute cartridge magazine supported upon said shaft between said barrel and said breech portion; said cartridge magazine having peripherally arranged index indentations; a finger trigger; a hammer; a firing pin; resilient means for normally urging said hammer in contact with said firing pin; a member pivotally connected to said trigger and having a portion engageable with said hammer for retracting and releasing the latter to engage the firing pin upon movement of the trigger and another portion movable into the path of the indentations on said cartridge magazine for indexing the latter; adjustable means carried by said trigger and engageable with said member for determining the coordination of the magazine indexing portion and the release of the hammer; 10 and means carried by said trigger for locking the adjustable means in predetermined position.

CHARLES J. MANVILLE.
